UNITED STATES PATENT OFFICE.

KARL SALO AND MICHAEL SHERMAN, OF INDIANAPOLIS, INDIANA.

POWER-HAMMER.

1,255,793.

Specification of Letters Patent.

Patented Feb. 5, 1918.

Application filed September 5, 1916. Serial No. 118,496.

To all whom it may concern:

Be it known that we, KARL SALO and MICHAEL SHERMAN, citizens of the United States, residing at Indianapolis, in the county of Marion and State of Indiana, have invented a new and useful Power-Hammer, of which the following is a specification, reference being had to the accompanying drawings and to the letters and figures of reference marked thereon.

This invention relates to the type of power hammer that is designed to be operated rapidly and with moderate power on metals, more especially for shaping sheet metal to various forms, the invention having reference more particularly to the type of power hammer in which the body of the hammer is actuated and controlled by means of a spring or elastic yoke that is connected with a crank pin, the latter being operated under control at intervals by means of suitable clutch connections.

An object of the invention is to provide improved means whereby to connect the hammer body to the controlling spring in machines of the above-mentioned character, which connecting means shall be strong and durable in order that burdensome expenses for renewals and repairs may be avoided and thereby a great saving in cost of material and labor effected. Another object is to provide improved means for operating and controlling the clutch mechanism whereby the operation of the hammer is controlled, in order to attain durability and efficiency in an improved manner and avoid loss of time and expense usually entailed because of the necessity for making frequent repairs to the machine.

With the above-mentioned and other objects in view the invention consists in improved means whereby a hammer body is connected to an elastic yoke, the invention consisting also in improved means for operating and controlling a clutch device; and, further the invention consists also in the novel parts and combinations and arrangements of parts as hereinafter particularly described and further defined in the accompanying claims.

Referring to the drawings,—Figure 1 is a front elevation and Fig. 2 a side elevation of a popular type of power hammer to which the invention is applied. Fig. 3 is a fragmentary section on the line III—III on Fig. 2. Fig. 4 is a perspective view of one

of the parts of the improved means for connecting the hammer body to its operating yoke. Fig. 5 is a section on the line V—V on Fig. 1. Fig. 6 is a perspective view of the improved hammer body. Fig. 7 is a section on the line VII—VII on Fig. 2. Fig. 8 is a fragmentary section on the line VIII—VIII on Fig. 1. Fig. 9 is a fragmentary section also on the line VIII—VIII. Fig. 10 is a perspective view of the improved devices comprised in the connections between the hammer body and its operating yoke. Fig. 11 is a central section of one of the rollers with which the machine is commonly provided. Fig. 12 is a vertical section of the hammer body on the line XII—XII on Fig. 7. Fig. 13 is a section on the line XIII—XIII on Fig. 2. Fig. 14 is a perspective view of the improved roller comprised in the improved clutch controller.

Similar reference characters on the different figures of the drawings indicate like elements or features of construction herein referred to in detail.

The particular machine with which the invention is illustrated and to which the invention is advantageously applied comprises a pillar 1 which supports a table in the form of a projecting arm 2 having an anvil 3 thereon provided with a removable die or block 4. The pillar supports also a frame 5 above the arm which has a guide head 6 on its end, a driving shaft 7 being rotatably mounted in the frame and having a crank plate or disk 8 secured thereto which a crank pin 9 is adjustably connected so as to vary the length of stroke of the hammer. A connecting rod 10 is connected to the crank pin and has a bow-shaped spring or flexible yoke 11 secured thereto. Two links 12 and 13 are pivotally connected to one end of the spring or yoke and the links have a roller 14 connected thereto. Two links 15 and 16 are pivotally connected to the opposite end of the spring or yoke and have a roller 17 connected thereto. A hammer body 18 is guided for vertical movement on the guide head 6 and has a suitable die or hammer head 19 removably connected thereto to coöperate with the die or block 4 of the anvil. The hammer body 18 has a transversely arranged aperture 20 therein to receive the devices whereby the body is connected in an improved manner with the rollers 14 and 17, the rollers constituting pivotal connecting devices.

In carrying out the objects of the invention the hammer body 18 is provided with holes 21 and 22 forward of the aperture 20 and also sockets 23 and 24 rearward of the 5 aperture to form pivot bearings in which pivots 25 and 26 are removably supported, one pivot extending through the bearing 21 across the aperture and into the bearing socket 23, the other pivot being likewise arranged in the remaining bearings. Preferably the pivots are provided with incasing rollers 27 and 28 respectively. The pivots are secured in place by suitable means preferably comprising a retaining pin 29 which 10 is inserted in a pin hole 30 with which the body 18 is provided, the pin extending through a pin hole 31 with which each pivot is provided. The retaining pin is suitably secured in place, being preferably provided 15 with a head on one end and a key 32 in its opposite end. The rollers 27 and 28 preferably have oil holes 33 therein. Two metallic links are provided for connecting the hammer head with the elastic yoke and preferably 20 are composed of steel, one link having a straight main portion 34 on the ends of which are crooks 35 and 36, one crook embracing the roller 14 and the other embracing the roller 27. Both links are alike, the 25 remaining link having a main portion 37 on which are crooks 38 and 39, one crook embracing the roller 17, the other embracing the roller 28. The arrangement of the links that connect the hammer body with the yoke 30 is such that permits free pivotal movement 35 of the links when the yoke rocks relatively to the hammer body as the crank pin 9 is carried about the axis of the shaft 7, with the minimum resistance and wear in the 40 pivotal connections.

In the machine described the shaft 7 has a pulley 40 rotatably mounted thereon and driven by a belt 41, the pulley being provided with a suitable clutch device 42 which 45 is adapted to be frictionally engaged by a metallic clutch sleeve 43 that is splined on the shaft and has a circumferential groove 44 to receive controlling devices. When operating the machine the clutch sleeve is frequently moved with the result that the side walls of the groove are rapidly worn away, and the faces of the walls become deformed due to uneven wear of the metal thereof. A shifter is provided which has two arms 50 45 and 46 and is supported on a pivot shaft 47 mounted on the frame 5 and provided with an operating arm 48 which may be variously operated, being preferably connected by suitable means with a spring- 55 retracted foot lever 49 mounted on the pillar 1 of the machine. The arms 45 and 46, in carrying out the object of the invention, are provided with metallic stub axles 50 and 51 respectively that extend into the groove 44 60 and have rollers 52 and 53 thereon that con-

tact with the side walls of the groove, the rollers being composed of metal of different character from that of which the clutch sleeve is composed; and, the rollers are provided respectively with wearing bushings 54 70 and 55 that are fixed in the rollers and composed of suitable metal that differs in character from that of the metal of the axles on which the bushings rotate. The metals are of suitable character to enable the several 75 parts to operate with the minimum amount of wear when not supplied with lubricating oil and permit the rollers to rotate in contact with the wall of the groove 44, especially on being forced into contact therewith when the clutch sleeve is forced into contact with the clutch device of the pulley. 80

In practical use the pulley 40 may rotate idly on its shaft until the workman arranges his work, and when hammering is 85 required the operator causes the clutch shifter to be moved to bring the clutch sleeve forward into contact with the clutch device 42 which enables the pulley to rotate the driving shaft 7 to operate the hammer in 90 the customary manner but without entailing destructive wear of the appliances whereby the hammer body is connected with the elastic yoke or spring 11, excessive wear and renewals of the stub axles or pins 50 and 51 95 being also avoided as a result of the present improvement.

Having thus described the invention, what is claimed as new is—

1. In a power hammer, the combination 100 of a hammer body having an opening therein, two pivots connected to the hammer body and extending across the opening therein, two rollers on the pivots respectively within the opening, two metallic links 105 comprising each a straight main portion and a crook on each end thereof, one crook of one of the links embracing one of the rollers, one crook of the remaining link embracing the remaining roller, a roller embraced 110 by the remaining one of the crooks of one of the links, a roller embraced by the remaining one of the crooks of the remaining link, two pivots in the two last-described rollers respectively, and two pairs of links, 115 one pair being connected to one of the last-described pivots, the remaining pair of links being connected to the other of the last-described pivots, with means for movably guiding the hammer, and means connected 120 to the pairs of links for moving the hammer body.

2. In a power hammer, the combination 125 of a hammer body having an aperture therein and also pivot bearings on opposite sides of the aperture, the body having also a pin hole extending therethrough and intersecting the pivot bearings, two pivots extending through the aperture and seated in the bearings on opposite sides of the aperture, each 130

- 5 pivot having a pin hole therein, two rollers on the pivots respectively within the aperture, a retaining pin inserted in all the pin holes, a securing device holding the retaining pin in the pin holes, and two links connected to the rollers respectively, with means for movably guiding the hammer body, and means connected to the links for moving the hammer body.
- 10 3. In a power hammer, the combination with a frame, a hammer body movably guided by the frame, a shaft rotatably mounted on the frame, means connected with the shaft and the hammer body adapted to operate the body, a pulley rotatably mounted on the shaft and having a clutch device thereon, and a metallic clutch sleeve splined on the shaft and adapted to be engaged with the clutch device, the sleeve hav-
- 15

ing a circumferential groove therein, of a 20 shifter lever pivotally mounted on the frame and having two arms provided each with a metallic stub axle that extends into the groove, each axle having a metallic roller thereon to contact with the opposite walls 25 of the groove, the roller having a metallic bushing therein that bears on the stub axle and differs from the character of the metals of the axle and the roller, the metal of the roller differing from that of the sleeve. 30

In testimony whereof, we affix our signatures in presence of two witnesses.
